UNITED STATES PATENT OFFICE.

FRED C. THOMPSON, OF OAKLAND, CALIFORNIA.

WRENCH.

1,411,135.

Specification of Letters Patent. Patented Mar. 28, 1922.

Application filed July 6, 1920. Serial No. 394,140.

To all whom it may concern:

Be it known that I, FRED C. THOMPSON, a citizen of the United States, residing at Oakland, in the county of Alameda and State of California, have invented certain new and useful Improvements in a Wrench, of which the following is a specification.

This invention relates to a wrench and has for its principal object the production of a device of this nature which is provided with a fixed jaw and a movable jaw, said movable jaw being provided with operating means so that same may be firmly held in engagement with the object upon which it is desired to use the wrench.

Another object of the invention is to generally improve upon wrenches of this character by providing a device which will be extremely simple, durable and inexpensive in construction, one which is efficient and reliable in operation, and well adapted to the purpose for which it is designed.

With these and numerous other objects in view the invention resides in certain novel features of construction, the combination and arrangement of parts as will be herein-after fully described and claimed.

In the accompanying drawing:—

Figure 1 is a vertical longitudinal section taken through the wrench.

Figure 2 is a fragmentary side elevation of the upper portion of the wrench.

Figure 3 is a horizontal section taken above the movable jaw of a modified form of the wrench, and

Figure 4 is a fragmentary side elevation of this modification showing portions thereof in section.

Referring to the accompanying drawing by numerals it will be seen that 1 designates the handle which is provided with the fixed jaw 2 having the teeth 3 upon its face which may be of any preferred construction. The lower portion of the handle is provided with the bore 4 for receiving the spiral shank 5 which comprises the shank 6 and the threaded portion 7. The threaded portion 7 is of substantially the same size as the vertical slot 8 which receives the reduced portion of the slideable jaw 10. The outer face of this reduced portion 9 is provided with threads which mesh with the threaded portion of the spiral screw 5. In order to hold the slideable jaw in engagement with

the threads I have provided a plurality of 55 U-shaped bands 11 which fit around the handle 1 and are fixedly attached to the sliding jaw 10 by any suitable means such as rivets 12. Upon the sliding jaw 10 I have mounted the locking jaw 13 which is provided with the depending ears 14 which are in rockable engagement with the sliding jaw by means of the pin 15. In order to hold the inner portion of the jaw in a raised position I have provided the leaf 65 spring 16 which is held in place by means of the rivet 7.

In order to hold the spiral screw 5 within the bore 4 I have provided at the top thereof a bore 18 which fits within socket provided in the block 19. This block 19 is held within the fixed jaw or the upper portion of the handle by means of the pin 20 as is shown in Figure 1 of the drawing.

By referring to Figures 3 and 4 of the drawing it will be seen that the modification consists of the handle 1 and the fixed jaw 2. This fixed jaw, however, is not provided with teeth but has the smooth face 3'. The sliding jaw 10 is similar in construction to 80 that already described being held in place by the handle 11 but is not provided with the locking jaw as in the above described modification. It will therefore be seen that this modification is especially adapted for 85 gripping nuts while the above modification is used for gripping pipes and the like.

Upon the lower end of the spiral screw 5 in both modifications I have provided a knob 21 which has the outer surface thereof 90 frictionally formed so that same may be easily grasped for tightening the sliding jaw as will be readily understood.

From the foregoing description, taken in connection with the accompanying drawings, 95 the construction and operation of the device will be readily understood without a more extended explanation. As numerous changes in form, proportion, and in the minor details of construction, may be resorted to without 100 departing from the spirit of this invention, I do not wish to be limited to the construction herein shown and described other than as claimed.

Having thus described my invention what 105 I claim as new is:—

A device of the class described comprising a handle having a longitudinal bore, a fixed

jaw, a slid able jaw, a U-shaped band having its ends fixedly secured to said slid able jaw so as to hold the same in slid able relation with the handle, a spiral screw mounted in 5 said bore and adapted to engage said slid able jaw for operating the same, a ball formed on the inner end of said spiral screw, and a block situated wholly within the fixed

jaw and provided with a socket for receiving said ball.

In testimony whereby I affix my signature in presence of two witnesses.

FRED C. THOMPSON.
